UNITED STATES PATENT OFFICE.

JACOB B. BEAM, OF PUNXSUTAWNEY, PENNSYLVANIA.

RADIATOR.

1,019,122.

Specification of Letters Patent.

Patented Mar. 5, 1912.

Application filed February 16, 1911. Serial No. 608,944.

To all whom it may concern:

Be it known that I, JACOB B. BEAM, a citizen of the United States, residing at Punxsutawney, in the county of Jefferson and State of Pennsylvania, have invented certain new and useful Improvements in Radiators, of which the following is a specification.

My invention relates particularly to radiators of the class employed on automobiles to cool the water which circulates in the jackets of the engine cylinders, and the object of my invention is to provide a radiator of this class which shall be strong and durable, not liable to leak and which can be easily repaired when for any unusual reason any of the parts are accidentally broken.

A further object of my invention is to so construct the radiator that any desired design may be employed for the front thereof and yet radiator sections may be employed which can be inserted in or removed from the rear portion of the radiator frame without detaching any part of the front frame or disfiguring the front frame with fastening devices.

A further object of my invention is to provide circulating tubes of improved construction in which the water as it circulates is more thoroughly agitated and brought into contact with the cooling surfaces.

Other features of my invention will be more fully hereinafter explained.

In the accompanying drawings,—Figure 1 is a view in front elevation with parts broken away and parts in section of an automobile radiator with my improvements applied. Fig. 2 is a detail view in horizontal section of one of the radiator tubes. Fig. 3 is a perspective view of the radiator with parts broken away and parts in section to more clearly show other parts. Fig. 4 is a detail view in perspective showing the construction of the upper portion of the radiator frame at the front and side thereof. Fig. 5 is a perspective view of one of the independently removable radiator sections. Fig. 6 is a perspective view of the lower front portion of one side of the radiator frame. Fig. 7 is a detail view in dotted lines showing how the bottom of the radiator frame containing the lower water chamber is lowered away from the side frames when it is desired to remove one or more of the radiator sections. Fig. 8 is a side elevation of the radiator shown in Figs. 1 and

3 with parts in section and parts broken away for the purpose of illustrating other parts. Fig. 9 is a detail view on an enlarged scale and in section showing more clearly the construction of a radiator section. Fig. 10 is a detail view in perspective and in section showing how the headers of the radiator sections are constructed. Fig. 11 is a perspective view of a portion of a radiator tube. Fig. 12 is a similar view but showing the parts in section. Fig. 13 is a plan view of a blank from which a radiator tube constructed in accordance with my invention is made.

The upper water chamber A is cast in one integral piece without seam and it has cast integrally with it a front frame consisting of the front pieces a and side frames consisting of the side pieces a' , (see Fig. 4). The front and side frames extend downwardly, as indicated in Fig. 8, and are formed integrally with a bottom front piece a^4 . It will thus be seen that the upper water chamber, the sides and the front of the radiator frame are all cast together without seam and there is no danger of seams being opened by vibration or unequal heating and a rigid connection can be formed between the upper and lower parts of the frame as will next be described.

The side pieces a' of the radiator frame are formed on opposite sides with laterally projecting ears a^2 on which rests the sheet metal ornamental cover A' which is secured to the frame by means of screws a^3 applied at suitable points. Below the ears a^2 the sides a' are formed with ears or flanges b , as clearly shown in Figs. 1 and 6. The filling tube X has a threaded connection at w with the top of the upper water chamber A and it is provided with a removable cap X'. By removing the screws a^3 and the tube X the cover A' may be lifted up and removed from the radiator frame. This cover A' may be stamped or pressed from a single piece of sheet metal and is not permanently connected or formed with the radiator frame as in prior constructions.

The lower water chamber C is formed in the bottom part B of the radiator frame. This bottom part of the frame, the construction of which is clearly indicated in Figs. 1 and 3, comprises a bottom c , sides c' and a top c^2 . The sides c' extend above the top c^2 and their upper edges are flush with the upper edges of the frame piece a^4 .

The ends of the water chamber are closed at c^3 and the upwardly projecting portions of the ends are formed with laterally projecting ears or flanges c^4 which are arranged directly below the ears or flanges b .
 5 Bolts D are employed to securely connect the bottom frame B with the side frames. This is clearly illustrated in Figs. 1 and 8. Rubber washers z and metal washers z' are threaded on the bolts and are interposed between the heads of the bolts and the flanges c^4 . In this way a pressure is produced which holds the joints tight but relieves the strain when it is abnormal. By
 10 this construction the bottom of the radiator frame may be separated from the other portions of the frame or readily connected therewith. The top wall c^2 of the water chamber C is formed with a series of bosses d having seats d' containing packing, as shown, and adapted to receive bosses on the radiator sections, as hereinafter described. The chamber C is inclined at the bottom from one side of the radiator to the other,
 15 20 as indicated in Fig. 1, where it is connected with an outlet E in turn connected with the water jackets of the engine. e indicates a draining cock.

Returning now to the upper part of the radiator, the part F is a lug constructed to receive the hinge rod of the hood commonly employed in automobiles and the part marked F' is adapted to receive a rod extending to the dash-board of the
 30 35 automobile. The hood is received in the depressed portion f of the top wall of the upper water chamber which chamber is provided with a connection F² for a pipe leading to the water jackets of the engine.
 40 The bottom wall of the water chamber A has a horizontal portion g formed with bosses g' having packed seats for corresponding bosses on the upper ends of the radiator sections and the horizontal portion g is connected by an inclined portion g² with another horizontal portion g³ at a lower level than the part g. In this way a recess is formed in the bottom of the water chamber A adapted to receive the top headers of the radiator sections so that the lower walls thereof are above the plane of the top edge of the opening in the radiator through which air circulates. Thus the upper header is hidden from view and does not
 45 50 55 obstruct the passage of air through the radiator. By providing the inclined wall g² space is economized and the radiator heads are made to fit closely in place and can be easily detached. The upper and lower water chambers are connected by vertically arranged radiator tubes which extend at their upper and lower ends into headers, which headers communicate with the water chambers. These headers are made in sections
 60 65 which with the tubes connected with them

are separately removable from the radiator frame. In the drawings I have shown each set of headers carrying five radiator tubes and have illustrated six sets of headers with corresponding tubes. These sections 70 are independent of each other and can be separately removed from the radiator frame or inserted therein. Each radiator section comprises an upper header H and a lower header I connected by vertical tubes 75 J. The headers H and I are of substantially the same construction, and the details of construction of one of them is shown clearly in Figs. 9, 10 and 11. The part h, which comprises the top, sides and ends of 80 the header, is made of a single casting while the part h' is preferably made of sheet metal joined in any suitable way at h² to the lower edge of the casting. The top of the casting is formed with an annular boss 85 or flange h³ adapted to enter a socket at g' (see Fig. 8). The lower header, while of the same construction, is of course, reversed, the part h' being at the top and the boss h³ at the bottom. The part h' is of 90 the construction shown more clearly in Fig. 10, consisting of a slotted plate having beveled edges h⁴ adapted to connect with the beveled edges h⁵. If the header H were cast all in one piece, i. e., with the bottom 95 h' formed integrally it would be difficult and expensive to form the slots in the cast metal to receive the tubes J, but by making the part h' of sheet metal, it can be stamped into shape with the slots by an inexpensive 100 operation. In this way the cost of the header is considerably reduced.

The tubes J are made in an improved way. Fig. 13 illustrates the formation of the blank for this purpose. A sheet of metal K is 105 formed with two series of parallel grooves k, k' which have on the opposite sides corresponding ribs. Between alternating parallel grooves are formed transverse relatively short grooves and indentations k². It 110 will be observed by reference to Fig. 13 that the grooves and ribs k² in the top series at the right hand side are three in number and are in line with a space between the two uppermost grooves and ribs on the opposite side 115 of the sheet which has no parts k². In the next space, however, between the ribs k' at the left there are the parts k² which are four in number and which are in line with a blank space k⁵ at the opposite side of the 120 sheet. The blank in this condition is bent on the line L until it assumes the condition shown in Fig. 11, the edges being overlapped and secured at l by solder so as to make a water-tight joint. The construction 125 of the tube thus formed is more clearly illustrated by the sectional view, Fig. 12, where it will be seen that the tube has a channel running through it from top to bottom which is formed with lateral offsets at k' 130

which branch in opposite directions and between each two of which offsets or grooves k' there are vertically arranged projections k^2 , the construction being such that as water 5 passes downward through the vertical channel it spreads into the offsets k' and then passing down past the projections k^2 the water is divided and agitated, then spread into the next offsets k' and so on. This irregular movement of the water through the 10 tubes so agitates it that it is brought more intimately into contact with the walls of the tube and into the range of action of the cooling air which passes between the tubes. 15 The projections k^2 , in addition to the function above described, also serve to hold the opposite sides of the bodies of the tubes apart and properly spaced. The tubes thus 20 constructed are connected with the upper and lower headers in the manner indicated in Fig. 9. The lower ends of the tubes are first passed into suitable openings in the top wall of the lower header I and are soldered 25 therein, and then the upper ends of the tubes are connected with the lower plate h' of the upper header and are soldered thereto. Before soldering, the tubes are inserted 30 to a sufficient extent to provide a space between the upper wall of the top header and the lower wall of the bottom header that will just fill the space between the bottom 35 wall g of the upper water chamber and the upper wall c^2 of the lower water chamber, so that a tight joint may be formed between the upper and lower ends of the radiator 40 section and the walls of the water chambers. In order to insert the radiator sections, the bottom section B of the frame containing the water chamber C is detached from the 45 frame, then the radiator sections are inserted, the bosses or flanges h^3 fitting into the sockets in the bosses g' in the upper water chamber which, as before described, are packed. When this is done the lower section B is lifted, the bosses h^3 are made to 50 enter the sockets in the bosses d , which are properly packed, and then the bolts D are screwed home to firmly and rigidly connect the parts. All of the radiator sections are applied in the same way. Any one of them 55 may be separately detached, it being necessary for this purpose only to remove the bolts D , or to unscrew them to a sufficient extent to allow the bottom section B to lower to a sufficient extent to permit the bosses h^3 to be separated from their sockets, then any section may be removed without disturbing the others and may be replaced by a new one, or the openings to which they 60 were connected may be plugged temporarily so that on the road the radiator may be used with one section removed for a time or until a repair shop is reached. The offsets k' not only provide for the lateral spread of the 65 water, but as clearly shown in Fig. 9, the

offsets abut against each other, hold the tubes properly spaced and brace them so that a rigid structure is obtained.

The construction shown and described is such that the radiator sections are supported not entirely by securing bolts but mainly by the bottom of the radiator frame, means being provided for quickly removing an injured radiator section and replacing it. The joints are all tight. There is no danger of leakage and the radiator tubes are of such construction as to insure such a circulation of water as to quickly cool it, and the construction of these tubes is also such that they mutually support and brace each other. 70 75 80

I claim as my invention:

1. A radiator, comprising upper and lower water chambers, a frame connecting them; a series of radiator sections resting on the top of the lower portion of the frame 85 and each comprising two headers having communicating ports with the water chambers, and connecting tubes each comprising a tubular body portion having horizontally arranged grooved offsets forming lateral 90 water spaces and vertically arranged projections between the offsets extending from one side of each tube to the other side thereof for holding the sides of the tubes apart.

2. A radiator section, comprising upper 95 and lower heads and tubes connecting them, each comprising a body portion having horizontally arranged grooved offsets forming lateral water spaces in the tubes and vertically arranged projections interposed between the horizontal offsets extending from one side of each tube to the other side thereof and holding the sides of the tubes apart. 100

3. A radiator section, comprising upper and lower headers and tubes connecting 105 them each made from a single piece of sheet metal bent upon itself and joined at one vertical edge and provided with horizontally arranged grooved offsets forming lateral water spaces in the tubes and other offsets 110 or projections interposed between the horizontal offsets which hold properly spaced the sides of the tube and serve to deflect or divide the water as it passes through the tube. 115

4. A radiator section, comprising upper and lower headers, and a series of tubes connecting them each made from a single piece of sheet metal bent upon itself and joined at one vertical edge, said tubes being provided with grooved offsets forming lateral water spaces in the tubes and which offsets in different tubes abut against each other and hold the tubes properly spaced. 120

5. A radiator section, comprising upper 125 and lower headers and tubes connecting them, each header comprising a casting formed in one piece constituting the sides, ends and top or bottom of the header, and a separate sheet metal slotted bottom or top 130

1
secured watertight to the casting and to which the tubes are connected.

6. A radiator, comprising an upper water chamber formed in one piece without seam and formed integrally with the sides and bottom front piece of the frame; a separately formed lower water chamber, means for detachably connecting this water chamber with the sides of the radiator frame, and 10 radiator sections interposed between the upper and lower water chambers and resting on and supported by the lower water chamber.

7. A radiator, comprising an upper water chamber having a recess at the front of its 15 lower wall to receive the upper ends of the radiator sections and having sockets in its lower wall; a lower water chamber having an upper wall provided with sockets 20 adapted to connect with the lower headers of the radiator sections; and a series of

radiator sections formed with upper and lower bosses engaging the sockets in the walls of the upper and lower water chambers.

25 8. A radiator, comprising an upper water chamber formed in one piece without seam and formed integrally with the sides and bottom front piece of the frame, a separately formed lower water chamber, radiator 30 sections interposed between the upper and lower water chambers, flanges formed on the sides of the frame and on the opposite ends of the lower water chamber and bolts carrying soft washers for connecting the 35 flanges together.

In testimony whereof, I have hereunto subscribed my name.

JACOB B. BEAM.
